UNITED STATES PATENT OFFICE.

DANIEL W. MUNDEN, OF INDIANAPOLIS, INDIANA, ASSIGNOR TO LOUIS WAGSCHAL, OF INDIANAPOLIS, INDIANA.

ACETYLENE-GAS GENERATOR.

1,229,499.

Specification of Letters Patent. Patented June 12, 1917.

Application filed July 13, 1914, Serial No. 850,616. Renewed November 28, 1916. Serial No. 133,988.

To all whom it may concern:

Be it known that I, DANIEL W. MUNDEN, a citizen of the United States, residing at Indianapolis, in the county of Marion and State of Indiana, have invented a new and useful Acetylene-Gas Generator, of which the following is a specification, reference being had to the accompanying drawings and to the letters and figures of reference marked 10 thereon.

This invention relates to a machine or apparatus whereby gas is generated from carbide of calcium, the invention having reference more particularly to a gas generator 15 that is designed to withstand an extremely high pressure, and to rapidly produce the gas under various pressures.

An object of the invention is to provide a high-pressure acetylene gas generator that 20 shall be so constructed as to be adapted to be manufactured without entailing great expense, and which shall be adapted to be self-contained and to operate effectively in small sizes in order to permit shipment 25 thereof from the factory at the minimum cost for package and freightage.

Another object of the invention is to provide an acetylene gas generator which shall be so constructed as to be adapted to be 30 readily handled in operation whether of large or relatively small size and be capable of rapidly generating, and also containing gas, either under extremely high or under low pressure, with the purpose of immediately delivering the gas for use, or retaining 35 gas if desired for use as may be required.

A still further object is to provide an acetylene gas generator of such construction as to be especially adapted for generating 40 gas for charging gas-containers or packages under extremely high pressure to be used from the container or package for lighting or other purposes as may be required, the gas at high pressure in the generator being 45 useful also in supplying burners to produce a blow-flame for welding or other purposes.

With the above-mentioned and other objects in view the invention consists in an improved acetylene gas generator comprising 50 an open vessel for holding carbide of calcium, and an open reservoir for water to be fed to the carbide in the production of gas and provided with novel apparatus for controlling the feeding of the water to the 55 carbide-vessel, and a sealed receiver inclosing

the carbide-holding vessel and also the water-reservoir, for receiving the generated gas and insuring the distribution of the gas pressure equally on the carbide and the feed-water, the receiver being provided with an 60 outlet for delivering the gas, and water-feeding means coöperating with both the reservoir and the receiver. The invention consists also further in the novel parts, and in the combinations and arrangements of 65 parts, as hereinafter particularly described and further defined in the appended claims.

Referring to the drawings forming part of this specification, Figure 1 is an elevation of the improved generator constructed 70 substantially in accordance with the invention; Fig. 2 is a sectional elevation approximately on the line A A on Fig. 1 but with the cover of the receiver disconnected from the body portion of the receiver; Fig. 3 is 75 a top plan of the generator minus the cover thereof and partially broken away; Fig. 4 is an enlarged sectional view of attachments of the cover of the receiver; Fig. 5 is an enlarged sectional view of attachments of 80 the water-reservoir; Fig. 6 is a perspective view of a guide with which the water-reservoir is provided; Fig. 7 is a vertical section partially broken away on the line A A on Fig. 1; Fig. 8 is a perspective view of a 85 part of the water-feed controlling apparatus carried by the cover of the receiver; Fig. 9 is a perspective view of the water-feed valve with which the water-reservoir is provided; Fig. 10 is a perspective view of the complete 90 water-reservoir partially broken away; Fig. 11 is a perspective view of the complete carbide-holding vessel, and Fig. 12 is a fragmentary side elevation of the device shown in Fig. 8.

Similar reference characters in the different figures of the drawings indicate corresponding elements or features of construction herein referred to.

In practically carrying out the objects of 100 the invention a very strong cylindrical vessel is provided which constitutes the main or body portion of the receiver and comprises a bottom 1, and a cylindrical shell or wall 2 secured in a substantial manner and 105 tightly to the bottom 1. The upper end portion of the shell or wall has a joint ring 3 firmly secured thereto, the ring extending around the exterior of the shell to constitute a retaining flange which has a suitable num- 110

ber of recesses or slots 4 in its peripheral portion to receive clamp bolts, the under portion of the ring or flange preferably having recesses 5 therein that extend from the inner ends of the slots 4. A packing ring or gasket 6 is preferably provided of proper size to fit upon the joint ring and form an air-tight joint between the top of the body portion of the receiver and a cover 7 which is provided and adapted to close the top of the body portion, the cover being placed upon the gasket. A suitable number of clamp bolts 8 are provided and fitted loosely into the cover, each bolt having a lug 9 projecting from one side of its lower end so as to be seated in the recess 5 to prevent the bolt from turning when tightening a nut 10 with which the bolt is provided. The nuts are seated upon the top of the cover so as to carry the bolts when the cover is removed, and when the bolts are turned so that the lugs extend outwardly the bolts may be entered in the slots 4, after which they may be turned so that the lugs engage the ring or flange of the main or body part of the receiver. The middle portion of the cover 7 is provided with a suitable packing box 11 having a guide bore 12 therein at the lower end of which is a joint seat 13, the upper portion of the packing box preferably having a gland 14 therein engaged by a packing nut 15 screwed onto the packing box. A valve-operating rod is carried by the cover and comprises a cylindrical shaft portion 16 which is inserted in and extends through the packing box and has a collar 17 thereon provided with a valve face 18 which is normally seated on the joint seat 13 to prevent the escape of gas and also to prevent the rod from being forced outward, the outer end of the shaft portion having an operating hand wheel or knob 19 fixed thereon for turning the rod which extends through the packing in the packing box. The rod comprises also a squared portion 20 which extends downward beyond the collar 17 in alignment with the shaft portion 16 for rotatably turning the feed-valve of the reservoir, the squared portion having a pointed guiding end 21 adapted to lead the squared portion into a socket. The interior of the receiver, as will be seen, is free from projections or obstructions so that the shell or wall of the body portion presents a clear guiding surface.

A suitable carbid-holding vessel is provided which comprises a bottom 22 and a cylindrical side portion or wall 23 secured to the bottom, the vessel being of suitable dimension so as to be freely inserted into the receiver to rest upon the bottom 1 thereof, the vessel having an open top. The upper portion of the side or wall 23 preferably is provided with a swinging bail 24 for carrying the vessel, and when the latter is in-

serted in the receiver the bail rests against the wall 2 thereof. The vessel is preferably provided with guides for guiding it centrally in the receiver and preferably is provided also with means for supporting a water-holding reservoir above the vessel. Preferably the guides and supports respectively are combined in one and comprise arms which may suitably be composed of L-section angle bar suitably bent so as to form base or shank portions 25, 25', 25'', respectively, which are secured to the inner side of the upper portion of the vessel wall 23 and extend outward over the top of the wall to form inclined centering arms 26, 26', 26'', respectively, from which guide portions 27, 27', 27'', respectively extend nearly to the wall 2 of the receiver for centrally guiding the vessel therein.

An open top water-holding reservoir is provided which comprises a saucer-shaped bottom 28 on which is a side or wall portion 29, the bottom normally being supported on the arms 26, 26', 26'', so that ample space is provided for the escape of gas from the carbid-holding vessel and from beneath the reservoir to the interior of the receiver, the space also permitting free equalization of the gas pressure in the receiver and in the vessel. The bottom 28 is preferably provided with a valve casing 30 which has a nipple 31 extending downward beyond the bottom, a feed-duct 32 extending from the interior 33 of the casing downward through the nipple. The upper portion of the interior of the casing is provided with screw-threads 34, and apertures 35 are formed in the wall of the casing for admitting water from the reservoir to the interior of the casing in which a valve seat 36 is formed at the upper end of the duct 32. Preferably a pipe cross or rosette 37 is secured to the nipple 31 and has radially arranged distributing pipes 38, 38', connected thereto, the pipes having caps 39, 39', closing their ends, and the under sides of the pipes have perforations 40, 40', therein from which the feed water may drop onto the carbid in the vessel below. The pipes serve also as supporting feet for supporting the reservoir uprightly when removed from the receiver. Preferably the upper portion of the reservoir is provided with a guide 41 having a guideway 42 therein, the guide being provided with supporting arms 43, 43', 43'', which are suitably secured to the top portion of the wall 29 of the reservoir, the reservoir being provided with means for centrally guiding it in the receiver, the guiding means preferably comprising guide extensions 44, 44', 44'', formed integrally on the arms of the guide 41 and extending nearly to the wall 2 of the receiver. Preferably the arms are secured to the wall 29 by means of angle pieces 45, 45', 45'', secured

to the wall and the respective arms. For the purpose of feeding or stopping the flow of water from the reservoir, a valve stem 46 is provided which has a cylindrical guide portion 47 thereon that extends rotatably through the guideway 42 and has a squared socket 48 in its upper portion adapted to receive the squared portion 20 of the operating-rod and enable the rod to rotate the stem, the latter having screw threads 49 thereon that are in engagement with the screw threads 34 of the valve casing. The valve stem has also a needle-point feed-valve 50 on its lower end adapted to coöperate with the valve seat 36 for controlling the flow of water, the control being effected, when the receiver is closed and sealed, by means of the external wheel or knob 19. The socket 48 is sufficiently deep to afford clearance and permit the valve to be elevated from its seat without interfering with the guide point 21 of the operating rod. The clearance is sufficient to also permit the reservoir to carry up the valve stem 46 in case the vessel is overcharged with carbid and the expanded product or ash of the carbid rises to the bottom 28 and lifts the reservoir from its supports. The upper portion of the wall 2 of the receiver has an outlet pipe 51 connected thereto that is provided with a stop valve 52 for controlling the discharge of the gas produced in the receiver, a pressure gage 53 being suitably connected with the outlet pipe between the receiver and the stop valve, or obviously the gage may be otherwise connected with the receiver. A blow-off pipe 54 is connected also to the wall of the receiver and provided with a stop valve 55, an automatic safety valve 56 being connected with the escape pipe 54 between the receiver and the stop valve.

It should be understood that various modifications in the details of construction may fairly be made within the scope of the appended claims, the structure described in detail being such as may be preferred as advantageous embodiment of the invention.

In practical use the cover 7 is moved from the body portion of the receiver and carries the valve-operating rod with it. The carbid-holding vessel is charged with a suitable quantity of carbid, preferably from one-half to three-fourths of the capacity of the vessel, after which the vessel is inserted into the body portion of the receiver and placed on the bottom 1 thereof, the bail 24 being pushed over to rest position so as to clear the reservoir, which after having been nearly filled with water is placed upon its supporting arms, the valve 50 being on its seat. The cover 7 is again placed in position following the insertion of the squared portion 20 of the operating rod into the socket 48 of the valve stem, after which the lug bolts are turned to proper position and

tightened so as to draw the cover down tightly and seal the receiver. When it is desired to generate gas the wheel or knob 19 is turned in the proper direction, so that the rod causes the valve stem to rotate and cause the valve 50 to be lifted more or less from its seat as may be desired to produce the gas with the required rapidity. The capacity of the receiver is relatively small, as will be seen, and consequently the gas pressure increases rapidly therein, and when the pressure is sufficient for the purpose as indicated by the pressure gage 53 the gas may be drawn off for such purpose as may be desired, such as the charging of gas tanks or portable containers for shipment and from which the gas may ultimately be used for consumption in automobile or other lamps, or for other purposes. In case of over-pressure in the receiver, the excess gas promptly escapes from the safety valve 56, and when desired the valve 55 may be opened to permit the escape of gas into the atmosphere, especially if there be pressure in the receiver when it is necessary to remove the cover for recharging with carbid.

Having thus described the invention, what is claimed as new is—

1. An acetylene gas generator including a closed receiver, a water-reservoir supported in the receiver and comprising a bottom and a side wall, the bottom being provided with a valve casing having a nipple thereon extending below the bottom, a plurality of perforated pipes having communication with the nipple and extending radially therefrom, the pipes providing supporting feet for the reservoir, and a feed-valve arranged in the valve casing.

2. An acetylene gas generator including a cylindrical receiver, a water-reservoir in the receiver, means for supporting the water-reservoir above the bottom of the receiver, a center guide having arms secured to the upper portion of the reservoir, the arms having guide projections projecting beyond the reservoir approximately to the wall of the receiver, a valve casing connected to the bottom of the reservoir, and a valve in the casing having a stem extending through the center guide.

3. An acetylene gas generator including a cylindrical receiver, a carbid-vessel comprising a bottom and a side wall, the bottom of the carbid-vessel being supported in the receiver, a plurality of combined supporting and guiding devices secured to the inner side of the upper portion of the wall of the carbid-vessel and extending upward and over the top of the wall approximately to the cylindrical receiver wall on an inclined angle, a water-reservoir removably supported upon the devices, and a feed-valve connected with the bottom of the water-reservoir.

4. An acetylene gas generator including a receiver body comprising a bottom and a side wall, a carbid-holding vessel in the receiver body removably supported on the bottom thereof, a water-holding reservoir removably supported by the carbid-holding vessel in the receiver body and provided in its upper portion with a guideway, a feed-valve in the reservoir having a vertical stem 10 guided in the guideway, the stem having a squared socket in its upper end, a cover removably secured and sealed to the top of the side wall of the receiver body and provided with a packing box having a joint-seat in

its inner end, and an operating rod extending movably through the packing box and having a collar thereon provided with a valve face normally in contact with the joint-seat, the rod having a pointed squared portion extending removably into the socket 20 of the valve stem.

In testimony whereof, I affix my signature in presence of two witnesses.

DANIEL W. MUNDEN.
